(57) **CLAIM**

The ornamental design for a hand tool packaging as shown and described.

DESCRIPTION

FIG. 1 is a front perspective view of a hand tool packaging according to the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view of the hand tool packaging with a hand tool therein.

The broken lines represent portions of the hand tool packaging that form no part of the claimed design. The broken line showing of a hand tool in FIG. 8 illustrates environment and forms no part of the claimed design.

1 Claim, 8 Drawing Sheets
